UNITED STATES PATENT OFFICE.

LEON F. PARKHURST, OF PITTSFIELD, MASSACHUSETTS, ASSIGNOR TO GENERAL ELECTRIC COMPANY, A CORPORATION OF NEW YORK.

ELECTRIC HEATING DEVICE.

1,257,106.

Specification of Letters Patent.

Patented Feb. 19, 1918.

Application filed July 23, 1914. Serial No. 852,603.

To all whom it may concern:

Be it known that I, LEON F. PARKHURST, a citizen of the United States, residing at Pittsfield, county of Berkshire, State of Massachusetts, have invented certain new and useful Improvements in Electric Heating Devices, of which the following is a specification.

My invention has reference to the manufacture of electric resistance heating units, and more particularly to such as are provided with a flat heating surface and which may either be used independently as a stove or heater, or in conjunction with other heating apparatus. In devices of this character, it is, of course, necessary that the resistance member should be thoroughly insulated from the metallic parts of the heating device, and at the same time it is highly desirable that it should be in intimate thermal relation with the supporting metal plate in order that the thermal drop between the resistance member and the heating surface may not be so great as to require the heating element to be run at a temperature under which it rapidly deteriorates in order to produce the desired temperature at the working surface.

In one of its aspects, my invention has for its object the provision of a novel structure for securing the heating unit in intimate thermal relation with the plate and the method of producing this structure. My invention also provides simple and efficient means for largely restricting the amount of heat that is conducted from the working portion of the plate to the edges thereof and from thence to the support for the plate, thereby greatly decreasing the losses and adding to the efficiency of the device.

Another object of my invention is the provision of a heating device of the character indicated, which is simple, compact and efficient in operation.

Other novel features of my invention will be apparent from the description and will be fully pointed out in the claims.

For a fuller understanding of my invention, reference may be had to the accompanying drawing, in which Figure 1 is a vertical section of a heating device embodying my invention, and Fig. 2 is a sectional view showing more in detail the structure of the heating unit and of the parts by which the same is secured to the top plate.

Referring now to the drawings, 1 is a continuous freely exposed metallic flat top plate which may conveniently be made of sheet steel the surface of which is preferably treated by any known process to prevent corrosion, and is provided with a corrugation 2 which will ordinarily be annular in form. The heating unit A is preferably formed of a resistance element 3 surrounded by insulation 4 which is in turn inclosed in a continuous metallic sheath 5. The unit may be made by swaging or otherwise working down an ingot in a manner now well understood in the art. While the unit may be secured directly to the top plate, I prefer first to place the same between two perforated plates 6 and 7 of a size to be received within the annular corrugation 2. The plate 1 is now inverted and the plates 6 and 7, with the heating unit A arranged between them, preferably in the form of a helical coil, are placed within its pan-shaped center, brazing material is placed upon the whole, and the parts thus assembled are placed in a suitable furnace when the brazing material will melt and flow through the openings of the plates 6 and 7 and between the coils of the unit A, thereby firmly inclosing the plates with the heating unit against the top plate and affording a good heat conducting path between the unit and the top plate. The brazing material, solidified in the openings of the plates 6 and 7 and between the coils of the heating unit, is indicated by the reference numeral 8. The brazing material also runs between the plate 6 and the plate 1 so that a thin film is formed between these plates and the structure comprising the perforated plates 6 and 7 and the heating unit A are welded or alloyed to the top plate 1 at every point. While the heating unit may be secured directly to the top plate, I find in practice that the brazing operation which I usually utilize in securing the unit to the plate is apt to result in the warping of the top plate due to the difference in the coefficients of expansion between the top plate and the brazing material. The construction which I have above described leaves the top plate perfectly flat, as it will be seen that the brazing material touches the top plate only at separated points, and, since the plates 6 and 7 are made of a metal having substantially the same coefficient of expansion as the top plate, it is obvious that

the expansion of the plates with the heating unit and the brazing material secured thereto as a whole will be substantially the same as that of the top plate, and the top 5 plate will remain flat throughout the process of manufacture.

The heating unit A is provided with free 10 ends 9 bent at right angles to the plane of the top plate and preferably having the ends 15 of the resistance conductors bared at 10. These terminals are preferably formed larger than the resistance conductor and may be made in accordance with the method described in a patent issued to W. R. Whitney April 14th, 1914, No. 1,093,512.

I have here shown three different terminals 20 in order that different degrees of heat may be produced. Any desired number of terminals may, of course, be used.

20 A second imperforate plate 13 is bent upwardly at 14, reflexed downwardly at 15 and engages the inner edge of the downwardly turned portion 12 of the top plate, and the two are secured together as by welding, the flanges of the two plates thus constituting a support for the device, which may be received in an opening in the top of a range. This support is of limited area and allows of small heat conduction into 25 said range top. At the same time the main portion of the plate 13 is spaced from the top plate to form a chamber for the reception of a heat insulating material. This plate is provided with an opening 16 through which a terminal block 17 passes. This block is provided with a flange 18 by which the same is secured to the bottom plate and to an annular ring 20 located within the bottom plate 13 by means of 30 screws 19. The terminals 10 of the resistance unit are joined to outer terminals 21 by means of conductors 22, which may be brazed or otherwise secured to the terminals 9. When the parts thus far described 35 have been assembled, the insulating material 23, which is preferably in powdered form and which may be of a composition disclosed in Patents 1,072,413 and 1,072,414, which were issued to Walter Arthur, Sep- 40 tember 9, 1913, is dusted into the space between the heating unit and the bottom plate through the terminal block. The space within the terminal block surrounding the terminals 9 of the sheathed wire and the 45 conductors 22 is then filled with any suitable material, such as cement, and the bottom of the terminal block is then closed by a separate section 25 secured to the main portion of the terminal block by screws 24.

50 The corrugation formed in the top plate not only serves the purpose of forming a dish when the top plate is inverted and thus confines the brazing material to the parts where the same is utilized, but a more im- 55 portant feature and a permanent advantage

of the corrugation is that it interposes a space of high thermal resistance between the heating unit and the edge of the top plate and the stove, and it thus serves to greatly reduce the heat losses. Furthermore, this corrugation strengthens the top plate, and the groove formed thereby acts as a receptacle for the reception of any material that may boil over from a vessel located on the heating unit and thereby tends to prevent it from running between the heating device and the stove top and eventually reaching the electric connections. 70 75

In accordance with the provisions of the patent statutes, I have described the principle of operation of my invention, together with the apparatus which I now consider to represent the best embodiment thereof; but I desire to have it understood that the apparatus shown is only illustrative, and that 80 85 the invention can be carried out by other means.

What I claim as new and desire to secure by Letters Patent of the United States, is:—

1. In an electric heater comprising a sub- 90 stantially flat freely exposed top plate of good heat conducting material, a supporting edge for said plate, a heating unit mounted in close thermal relation to said plate and means for reducing the flow of heat from the 95 unit to the supporting edge comprising a corrugation between the heated surface and the edge.

2. An electric heater comprising a sub- 100 stantially flat freely exposed top plate of good heat conducting material, a supporting edge for said plate, a heating unit mounted in close thermal relation to said plate and means for reducing the flow of heat from the 105 unit to the supporting edge comprising a bend in the plate below the heated surface and between it and the edge.

3. The method of making a heating device comprising a continuous metallic plate and a sheathed resistance heating unit which 110 consists in forming a continuous corrugation upon the plate, and brazing the heating unit to the plate within the portion embraced by the corrugation.

4. The method of making a heating unit 115 in which a continuous metallic plate, two perforated metallic plates and an insulated heating unit are utilized in its formation, which consists in assembling upon the continuous plate the perforated plates with the 120 heating unit between and then causing brazing material to flow into the openings of the perforated plates and around the heating unit thereby anchoring the continuous plate, the perforated plate and the heating unit 125 together.

5. The method of making a heating unit in which a continuous metallic plate, two perforated metallic plates and an insulated heating unit are utilized in its formation, 130

- which consists in forming a continuous corrugation on the continuous plate, inverting the same, assembling the perforated plates with the heating unit therebetween upon the 5 continuous plate within the portion of the plate embraced by the corrugation and causing brazing material to flow into the openings of the perforated plates and around the heating unit.
- 10 6. In an electric heater, an envelop comprising upper and lower spaced metallic plates having their edges brought into engagement, secured together and bent downwardly to form an extension for supporting 15 the unit.
7. An electric hot plate comprising a substantially flat upper metallic plate and a lower metallic plate having their edges brought into engagement, secured together 20 and bent downwardly to form an extension for supporting the hot plate, said extension being located above the bottom of the plate, and an electric heating element supported 25 by said upper plate.
8. An electric hot plate comprising a substantially flat upper metallic plate and a lower metallic plate having their edges brought into engagement secured together and bent downwardly to form an extension 30 for supporting the upper plate, said exten-
- sion being located above the bottom of the plate, an electric heating element comprising sheathed wire associated with said upper plate, the terminals of the wire being brought downwardly through the bottom 35 plate.
9. In an electric heater, an envelop comprising a substantially flat top plate and a lower plate having its edges secured to said top plate, a heating unit intimately secured 40 to the under side of said top plate, the top plate being provided with an annular depression surrounding said heating unit, and a powdered heat insulating material filling the space between the two plates. 45
10. A heating device comprising an envelop formed of spaced metallic plates having their edges secured together, an insulated resistance heating unit inclosed within a continuous metallic sheath which is secured to the under side of the top plate, a terminal block secured to the other plate and a thermal insulating material filling the space between the two plates. 50

In witness whereof, I have hereunto set 55
my hand this 21st day of July, 1914.

LEON F. PARKHURST.
